DESIGN FOR A SCOOTER FOOTBOARD

Samuel A. Snell, Toledo, Ohio, assignor to The American-National Company, Toledo, Ohio, a corporation of Ohio

Application March 3, 1938, Serial No. 75,558

Term of patent 7 years

To all whom it may concern:

Be it known that I, Samuel A. Snell, a subject of the King of Great Britain and Northern Ireland, residing at Toledo, in the county of Lucas and State of Ohio, have invented a new, original, and ornamental Design for a Scooter Footboard, of which the following is a specification, reference being had therein to the accompanying drawing forming a part thereof, wherein:

Figure 1 is a top plan view of a scooter footboard embodying my new design;

Figure 2 is a side elevation thereof;

Figures 3, 4, 5 and 6 are cross sectional views taken respectively on the lines 3—3, 4—4, 5—5 and 6—6 of Figure 2;

Figure 7 is a cross sectional view taken on the line 7—7 of Figure 1;

Figures 8 and 9 are fragmentary longitudinal sectional views taken on the lines 8—8 and 9—9 respectively of Figure 1.

I claim:

The ornamental design for a scooter footboard substantially as shown.

SAMUEL A. SNELL.
